Primary Examiner — Sandra Snapp*Assistant Examiner* — Ieisha N Price(74) *Attorney, Agent, or Firm* — Knobbe Martens Olson & Bear LLP(57) **CLAIM**

The ornamental design for a camera enclosure, as shown and described.

DESCRIPTION

FIG. 1 is an upper left rear isometric view of a camera enclosure;

FIG. 2 is a lower right front isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines rendered in FIG. 8 of the drawings illustrate portions of the camera closure and form no part of the claimed design.

1 Claim, 6 Drawing Sheets(56)
